UNITED STATES PATENT OFFICE.

EMMERICH KRIEGL, OF GLAUCHAU, GERMANY.

CHENILLE-MAKING MACHINE.

Application filed March 28, 1927, Serial No. 179,142, and in Germany May 7, 1926.

My invention relates to winding and twisting mechanism particularly adapted for making a pile fabric known as round chenille, and my main objects are a substantial reduction in manufacturing costs and less floor space requirement for a given output, by the simultaneous production in one working course of an increased number of chenille strands; and for an improved and positive automatic control of the machine elements whereby the exhaustion of supply, or breakage of any of the pile forming or warp threads will be immediately detected irrespective of the careful watchfulness of the operator, thus reducing to a minimum defective waste production.

With these main objects in view, and with others that will appear later herein, my invention relates to improvements in the heretofore known machine construction as fully set forth and described in the following specification in connection with the drawings accompanying the same and forming part thereof, the novel features whereof are particularly pointed out in the subjoined claims.

In the drawings,—

Fig. 1 is mainly a diagrammatic longitudinal sectional view of essential features of a winding and twisting machine embodying my improvements; the known twisting mechanism being indicated merely by the warp-engaging rotated and traversed hooks.

Fig. 2 is an enlarged partial longitudinal sectional plan view showing mainly my improved receiving form for the pile-forming windings and guide for the inner warp threads; Figs. 2^a and 2^b being partial transverse sections at different portions in the length of said form.

Figs. 3, 4, and 5 are enlarged detail cross-sectional views of the form and parts cooperating therewith adjacent the pile cutting devices, taken respectively on the lines A—B, C—D, and E—F of Fig. 6.

Fig. 6 shows in side elevation the parts indicated in Figs. 3, 4 and 5.

Fig. 7 is mainly a partial end elevation, looking in the direction of arrow 7 of Fig. 6.

Fig. 8 is mainly a reverse end elevation of the showing of Fig. 6, looking in the direction of arrow 8 thereof.

Fig. 9 is an enlarged diagrammatic side elevation showing the upper and lower tiers of strands extending from the end of the winding form toward the twisting devices;

and Fig. 10 is mainly a corresponding end view thereof.

Fig. 11 is a partial longitudinal cross-sectional view of the rotary spool head and its hollow shaft support, indicating particularly my automatic mechanism operative upon exhaustion of supply or breakage of any of the pile-forming threads of the spools carried by said head.

Fig. 12 is a partial detail plan view indicating the automatic control mechanism for the series of twisting chenille strands.

Fig. 13 shows further automatic control mechanism applicable to the series of warp threads.

The general type of machine indicated in the drawings is of known construction, and comprises a hollow shaft 1, fixedly mounted in table bearings not shown, and rotatably supporting a belt driven spool head 2, the latter carrying one or more spools in suitable brackets permitting their ready removal and replacement and proper tensioning, so that the pile-forming thread supplied by said spools may be drawn off as required and led over a guide ring 5 fixed to said spool head 2.

Such thread or threads 4 have heretofore been wound or wrapped around some kind of form, spaced bars, or directly upon spaced belts extending beyond hollow shaft 1 and tauted and equally driven to feed the windings therealong, inner and outer warp threads being laid on said windings adjacent to and parallel with the spaced belts, and the cutting devices severing said feed windings between said belts, and such cut windings then being engaged by twisting together each respective pair of warps to produce two round chenille strands. To my knowledge, all heretofore known machines adapted for producing chenille strands, have by their inherent structure, been of such limited capacity, which is uneconomical in use of floor space and requires expensive duplication of machinery for a given output.

One of my main objects, as stated, is to avoid such waste and duplication, and my improvements, which will presently be described in detail, provide for increased output for a given floor space by the production in one working course of an increased number of simultaneously formed strands. And as a requirement of such increased production, it is essential that the windings be in-

creased in diameter or spread so that they may be severed at a number of places to form a number of lengths each adapted to form the pile of a strand; and furthermore each 5 such longitudinal line of severed lengths must be supplied with inner and outer warp threads and supported in proper position between the latter until engaged therewith by the twisting together of its respective pair of 10 warps.

As a preferred embodiment of a form suitable for my purpose I employ a form 7, which as shown in the drawings, is mainly of rectangular cross-section with one end supported within the hollow shaft 1 by a diametral taper pin 8, and its opposite free end extending in an axial plane beyond said shaft. Upon the form 7 the pile forming thread 4 is wound by the rotated spool head 2, said 20 warps being fed along said form by side feed belts 9, as heretofore, so as to lay said warps in regular convolutions and carry the latter to the cutting devices. The belts 9 are preferably of steel wire, and preferably 25 also I employ two such belts on each side of the form 7, extending longitudinally close to the side edges of the latter, and for part of the length thereof adjacent the hollow shaft 1, in edge guide ways, as indicated in Fig. 2^a. The 30 drawings show only the portions of said belts extending through the hollow shaft 1 and over thrust guide sheaves 10 at the free end of the form, and they may be on any known type, endless and extended over drive wheels, 35 or reciprocated between winding drums; in which latter case they are of sufficient length to form a commercial length of strand, and the reciprocation takes place between strand formations; but in either case they are traversed in the portion shown in the drawings 40 at equal and determined feed speed in the direction of the arrows.

My improved form 7, as shown, is adapted to produce as heretofore the usual pair of 45 edge chenille strands by laying within the warps 6 between the feed wires 9, a longitudinal inner warp thread, superimposing an outer warp thread on said warps by means of the thrust guide sheaves 10, and severing 50 said warps on opposite sides of said pair of superimposed warps. But to increase the number of chenille strands producible in one working course, I employ the entire surface of said form 7 as a guide for additional longitudinal warp threads, and preferably as 55 shown, to insure the proper lateral spacings of the latter, groove said form surface to provide determined guide ways 11 for said warps 12, and in the present instance, I form 60 the guide ways in the upper flat surface of the form directly opposite the guide ways in the under flat surface. The form 7, as shown, at the hollow shaft supported end is provided with the aforesaid edge guide ways for the 65 feed wires 9 and one warp thread, and with a

transverse guiding bridge 13, as shown more clearly in Fig. 2^a, extending outwardly from both upper and lower surfaces between the guide ways 11 to insure the proper laying of each warp 12 in its respective guide way 70 and prevent its displacement; and said form is reduced in thickness and the feed wire guide ways omitted beyond the guide ring 5 so that the windings 6 will lie directly on the longitudinal warps 12 and feed wires 9, as 75 clearly seen in Fig. 2^b, to avoid frictional contact with the form in their travel therealong, the warps 12 being traversed at equal speed with the wires 9 by the take-up motion of the twisting mechanism as will later 80 appear hereinafter. While the bridge 13 and guide-ways 11 are both shown, one may be used without the other.

The outer end of said form 7, between the thrust sheaves 10, is recessed as shown, to 85 provide a series of projecting lugs or tongues 14, extending between a series of cutting devices; the latter preferably consisting of pairs of rotated discs with their cutting edges overlapping within said recesses. And to facilitate the simultaneous cutting of the windings on both the upper and lower surfaces of the form, it is important that said windings may contact at their points of severance, without stretching of the same to avoid 90 breakage and insure an even line of cutting; and with this in mind, I preferably outwardly taper each projecting lug 14 so as to reduce its thickness, and at the same time round its opposite surfaces, its resulting 95 cross-section approaching an outwardly reducing oval as clearly shown in Figs. 4 and 5.

The outer pairs of said cutting devices 15 sever the upper and lower windings on opposite sides of the superimposed edge warps 100 lying between the feed wires 9 and fed by the thrust sheaves 10, to form a pair of chenille strands 16 by the twisting together of their warps by the usual twisting mechanism and in the manner heretofore commonly employed. My invention provides however for the simultaneous production of additional chenille strands by superimposing an outer warp thread over each of the series of inner warp threads 12 and twisting said pairs of 110 inner and outer warps together as heretofore to engage the respective portions of the cut windings extending laterally on each side of said pairs of warps.

With this object in view, I provide, as 115 shown, adjustably fixed upper and lower outer warp thread guide plates 17, 17, projecting respectively toward the upper and lower surface of the outer end of the form 7 adjacent the series of cutting devices 15 with the ends curved to provide clearance 120 for the latter and their surfaces having spaced guide ways 18 vertically aligned with the form guide ways 11 to receive the series of outer warp threads 19; guards 20 insuring 125

the accurate positioning of each warp in its respective guide way, and the ends of said plates being recessed, with the series of projections 21 formed thereby overlying and forming complementary supports with the upper and lower surfaces of the projecting lugs 14 for the intermediately lying portions of the windings as most clearly seen in Figs. 3, 4, 5, and 6. The warps 19, guided in the ways 18 of projections 21, are accurately laid on the windings 6 in directly superimposed position over the respective inner warps 4, and said cooperating supports 21, 21 and form projections 14 retain them in such position during the cutting of the windings intermediate such pairs of warps, and the latter are retained in position extending laterally between their respective pairs of warps until fixedly engaged there-between by the twisting together of said warp pairs in well known manner.

Such twisting of the pairs of warps causes a rotation of the cut windings intermediately engaged thereby, and in order that such rotation may be assisted by, and not retarded by the rotary knives, at its initial point between the latter and beyond the supports 21, 21 and 14, I preferably form the series of rotary knives with opposed rough and smooth sides in accordance with their respective rotations coinciding with or being opposed to the rotation of their respective intermediate chenille strand 22 or 22', as clearly indicated in Fig. 5 by the words "rough" and "smooth" and the arrow showing the rotary direction of the chenille strand.

Any known form of twisting mechanism may be employed in connection with my improvements above fully described, the same commonly comprising rotated warp engaging hooks 43 mounted in a reciprocated carriage 42 determinedly moved in a direction coincident with the traversed feed wires 9 by weights or the like, so as to traverse said warps at equal feed with the wires 9 and twist them together to form chenille strands 22, 22'; it being essential for my purpose that said carriage provide a rotated hook 43 for each pair of cooperating warps.

Due to the shape of the cooperating projecting supports 14, 21, 21, and to insure uniform chenille strands, I prefer to draw off the series of upper and lower strands 22 and 22' respectively, in divergent directions as clearly seen in Figs. 1 and 9, and furthermore to prevent objectionably sharp twist extending to said supports I preferably bend said divergent series at a point removed from said supports as indicated at the angles B B, beyond which they extend in spaced parallel relation to their respective hooks 43. And to insure a desirable equalized uniformity of twist throughout the length of each chenille strand I employ, as shown, cranks or cams 23, 23, connected by pairs of rods 24, 24, re-

spectively to a pair of short radially swinging arms 25 and a pair of longer radially swinging arms 26, each of said arms having a transverse portion extending across the series of chenille strands. And I so time the cams 23, 70 as to cause the engaging edge 27 of a long arm 25 to contact with the upper series of strands 22, while a corresponding edge on a short arm contacts with the series of strands 22', and reversely as the cams shift the other arms 25 into contact position. By the means shown, which of course may be varied, its essential feature being the spacings of contacts with the twisting strands maintaining the angle bends B at varying points in its length, I 80 reduce the twist in the divergent portions, say at the point of contact of a long arm, which twist will at once extend to the short arm contact as the latter engages and long arm disengages, and when long arm again contacts, the 85 twist will extend beyond the short arm contact to the initial point of twist, thus preventing harmfully tight twist from reaching to such initial point, and equalizing the twist imparted throughout the entire length of 90 strands formed.

It will be understood of course that the cooperating warp guides and severing devices are so mounted as to be capable of nice adjustment in the relation to one another as indicated by the crossed arrows so as to provide for accurate positioning for various requirements of differences in yarn weights and materials employed.

To accomplish a second main object, heretofore stated, of automatically controlling operations of the machine in case of exhaustion of supply or breakage of any thread, I provide means shown more fully in Figs. 11, 12 and 13.

In Fig. 11, I have shown the control applicable to the spools 3 on rotated head 2, such means, as preferably indicated, comprising a series of arms 28, one for each spool 3 employed, insulatedly mounted on spool head 2 100 with interposed insulation 29, and carrying a contact 30 in electrical contact with a cooperating contact 31, preferably in the form of a ring insulatedly mounted on hollow shaft 1, and connected by a wire, as shown, to a 105 source of electrical energy. 32, 33, and 34 represent thread guide eyes for each of the threads 4, eyes 32 and 34 being adjustably fixed to arm 28 so as to permit variations for differences in thread thicknesses and strength, 110 and varying centrifugal throw of the rotated head 2; while eye 33 is movable with its supporting post 35, vertically carried in arm 28, and a spring 37 normally retains its contact 38 out of engagement with cooperating contact 115 ring 39 mounted on shaft 1. 40 and 41 are screws to adjust the position of eyes 32 and 34 so as to position them in relation to eye 33 for the purpose heretofore stated. Contacts 39 act through shaft 1 which is preferably of 120

105

110

115

120

125

130

metal and connected by a wire shown to the source of electrical energy.

The action is such that the centrifugal force of rotation of head 2 and arms 28 carried thereby, tends to cause the post carried eyes 33 to shift their contacts 38 into engagement with ring contact 39, such action being partially resisted by springs 37 and further resisted by the tension tauted threads 4 between adjusted eyes 32 and 34. Should the supply of thread on any spool become exhausted, or any spool thread break, the resistance of such thread against its corresponding post guided eye 33 ceases, and centrifugal force will cause contact of its post end 38 with ring 39 to close an electrical circuit as clearly indicated. Such electrical circuit, when closed, may be utilized in any convenient manner to stop the machine, as by operating a power control clutch or motor switch as best suited for the purpose. Springs 37 merely prevent closing of the circuit when the machine is at rest, as for resupplying with spools, and screws 40 and 41 as shown, permit adjustment of eyes 32 and 34.

Fig. 12 shows the automatic control for the chenille strands, each strand hook 43 having a limited independent longitudinal movement in traversing carriage 42, such movement bringing its opposite end 47, provided with an electrical contact piece 44, into engagement with a yielding contact member 45; a spring of sufficient force only to move the hook 43 longitudinally when a strand breaks, insures such closing of an electrical circuit, and a stop 48 on the carriage limits the shaft movement against yielding contact 45. The operation is clearly shown and requires no further description.

Fig. 13 shows an automatic control which is applicable to any of the warp threads employed, and consists simply of a series of thread guide eyes 49, one for each warp, mounted in a frame bar 50 and independently movable therein by action of springs 51 to cause their depending ends to electrically contact with a contact plate 52. The tensioned warp threads normally raise said depending eye ends away from such contact due to the tension given the thread, and when such tension fails, as by breakage or exhausted supply, the corresponding eye contact will close the electrical circuit and act to stop the machine as above set forth.

From the foregoing detailed description of preferred means for accomplishing my main objects set forth, and other objects disclosed later in connection with specific features, I believe that the construction and advantages of my invention will be readily understood; and it is obvious that modifications and changes in the details disclosed may be readily made without departing from the spirit of my invention, the scope of which is defined in the following claims.

What I claim as my invention and desire to secure by Letters Patent, is:

1. A winding and twisting machine for simultaneously making numerous chenille strands, comprising means for winding a pile-forming thread; means for laying a series of opposed inner and outer warp threads for said windings and jointly feeding the same; a series of cutting devices for said windings in the feed path between each pair of warps; and a separate twisting device for each pair of warps.

2. In a winding and twisting machine for simultaneously making numerous chenille strands, comprising means for winding a pile-forming thread; means for laying a series of opposed inner and outer warp threads for said windings and jointly feeding the same; a series of cutting devices for said windings in the feed path between each pair of warps; and a separate twisting device for each pair of warps; a receiving form for said windings the surface of which is arranged to guide said series of inner warp threads in laterally spaced relation.

3. In a winding and twisting machine for simultaneously making numerous chenille strands, comprising means for winding a pile-forming thread; means for laying a series of opposed inner and outer warp threads for said windings and jointly feeding the same; a series of cutting devices for said windings in the feed path between each pair of warps; and a separate twisting device for each pair of warps; a receiving form for said windings having a cross-sectional surface forming warp-thread guide-ways arranged in laterally spaced relation corresponding with the lengths of pile thread required for each of the several chenille strands produced.

4. In a winding and twisting machine for simultaneously making numerous chenille strands, comprising means for winding a pile-forming thread; means for laying a series of opposed inner and outer warp threads for said windings and jointly feeding the same; a series of cutting devices for said windings in the feed path between each pair of warps; and a separate twisting device for each pair of warps; a receiving form for said windings of oblong cross-section having flat top and bottom surfaces forming warp thread guide-ways arranged in laterally spaced relation corresponding with the length of pile thread required for each of the several chenille strands produced.

5. In a winding and twisting machine for simultaneously making numerous chenille strands, comprising means for winding a pile-forming thread; means for laying a series of opposed inner and outer warp threads for said windings and jointly feeding the same; a series of cutting devices for said windings in the feed path between each pair of warps; and a separate twisting device for each pair

- of warps; a receiving form for said windings of oblong cross-section having flat top and bottom surfaces forming warp thread guide-ways arranged in laterally spaced relation 5 corresponding with the length of pile thread required for each of the several chenille strands produced, said guide-ways in the bottom surface being located immediately below the guide-ways in the top surface.
- 10 6. In a winding and twisting machine for simultaneously making numerous chenille strands, comprising means for winding a pile-forming thread; means for laying a series of opposed inner and outer warp threads for said windings and jointly feeding the same; a series of cutting devices for said windings in the feed path between each pair of warps; and a separate twisting device for each pair of warps; a receiving form 15 for said windings having warp guiding projections extending between said cutting devices.
7. In a winding and twisting machine for simultaneously making numerous chenille strands, comprising means for winding a pile-forming thread; means for laying a series of opposed inner and outer warp threads for said windings and jointly feeding the same; a series of cutting devices for said windings in the feed path between each pair of warps; and a separate twisting device for each pair of warps; a receiving form for said windings having warp guiding projections extending between said cutting devices, said 20 extensions having rounded top and bottom guide surfaces.
8. In a winding and twisting machine for simultaneously making numerous chenille strands, comprising means for winding a pile-forming thread; means for laying a series of opposed inner and outer warp threads for said windings and jointly feeding the same; a series of cutting devices for said windings in the feed path between each pair of warps; and a separate twisting device for each pair of warps; a receiving form for said windings the surface of which is arranged to guide said series of inner warp threads, the latter supporting said windings away from 25 said form surface.
- 50 9. In a winding and twisting machine for simultaneously making numerous chenille strands, comprising means for winding a pile-forming thread; means for laying a series of opposed inner and outer warp threads for said windings and jointly feeding the same; a series of cutting devices for said windings in the feed path between each pair of warps; and a separate twisting device for each pair of warps; a receiving form for said windings the surface of which is arranged to guide said series of inner warp threads in laterally 30 spaced relation, and guide means for said outer warp threads arranged to lay the lat- ter on said windings in superimposed relation 65 to said series of inner warps.
10. In a winding and twisting machine for simultaneously making numerous chenille strands, comprising means for winding a pile-forming thread; means for laying a series of opposed inner and outer warp threads for said windings and jointly feeding the same; a series of cutting devices for said windings in the feed path between each pair of warps; and a separate twisting device 70 for each pair of warps; a receiving form for said windings having inner warp guiding projections extending between said cutting devices, and outer warp guides having similar projections co-extending with said first 75 named projections and in spaced relation to the latter.
11. In a winding and twisting machine for simultaneously making numerous chenille strands, comprising means for winding a pile-forming thread; means for laying a series of opposed inner and outer warp threads for said windings and jointly feeding the same; a series of cutting devices for said windings in the feed path between each pair of warps; and a separate twisting device for each pair of warps; a receiving form for said windings having inner warp guiding projections extending between said cutting devices, and outer warp guides having similar projections co-extending with said first named projections and in spaced relation to the latter, the opposed surfaces of said projections being reversely curved. 80
12. In a winding and twisting machine for simultaneously making numerous chenille strands, comprising means for winding a pile-forming thread; means for laying a series of opposed inner and outer warp threads for said windings and jointly feeding the same; a series of cutting devices for said windings in the feed path between each pair of warps; and a separate twisting device for each pair of warps; said cutting devices comprising pairs of cooperating rotary edge-cutting discs, the opposed flat faces of adjacent pairs being respectively smooth and roughened. 85
13. In a winding and twisting machine for simultaneously making numerous chenille strands, comprising means for winding a pile-forming thread; means for laying a series of opposed inner and outer warp threads for said windings and jointly feeding the same; a series of cutting devices for said windings in the feed path between each pair of warps; and a separate twisting device for each pair of warps; a series of guide ways between said cutting devices each adapted to support a line of cut windings intermediate 90 a pair of superimposed warps. 115
14. In a winding and twisting machine for simultaneously making numerous chenille

strands, comprising means for winding a pile-forming thread; means for laying a series of opposed inner and outer warp threads for said windings and jointly feeding the same; a series of cutting devices for said windings in the feed path between each pair of warps; and a separate twisting device for each pair of warps; and means adapted to angularly deflect each of said pairs of warps beyond its 10 respective guide way.

15. In a winding and twisting machine for simultaneously making numerous chenille strands, comprising means for winding a pile-forming thread; means for laying a series of opposed inner and outer warp threads for said windings and jointly feeding the same; a series of cutting devices for said windings in the feed path between each pair of warps, and a separate twisting device for 20 each pair of warps; contact members for the series of forming chenille strands adapted to deflect their path of feed to their respective twisting devices.

25. In a winding and twisting machine for simultaneously making numerous chenille strands, comprising means for winding a pile-forming thread; means for laying a series of opposed inner and outer warp threads for said windings and jointly feeding the same; a series of cutting devices for said windings in the feed path between each pair of warps; and a separate twisting device for 30 each pair of warps; a pair of spaced alternately engageable contact members for the series of forming chenille strands adapted to varyingly deflect their path of feed to their respective twisting devices.

35. In a winding and twisting machine for simultaneously making numerous chenille strands, comprising means for winding a pile-forming thread; means for laying a series of opposed inner and outer warp threads for said windings and jointly feeding the same; a series of cutting devices for said 40

windings in the feed path between each pair of warps; and a separate twisting device for each pair of warps; a stop motion mechanism comprising an electric circuit and a thread-actuated circuit-closing contact member, and means actuated by a normally feeding thread to hold said contact in non-contacting position. 45

18. In a winding and twisting machine for simultaneously making numerous chenille strands, comprising means for winding a pile-forming thread; means for laying a series of opposed inner and outer warp threads for said windings and jointly feeding the same; a series of cutting devices for said windings in the feed path between each pair of warps; and a separate twisting device for 50 each pair of warps; a stop motion mechanism comprising an electric circuit and a pile-thread actuated contact normally held in circuit-closing position by the centrifugal throw of said winding means, and means actuated by a normally feeding pile thread to hold said contact in non-contacting position. 55

19. In a winding and twisting machine for simultaneously making numerous chenille strands, comprising means for winding a pile-forming thread; means for laying a series of opposed inner and outer warp threads for said windings and jointly feeding the same; a series of cutting devices for said windings in the feed path between each pair of warps; and a separate twisting device for each pair of warps; a stop motion mechanism comprising an electric circuit and a circuit-closing contact carried by each of said twisting devices, said contact being normally held in non-contacting position by the tension of the warps respectively engaging said twisting devices. 60 65 70 75 80 85

In testimony whereof I affix my signature.

EMMERICH KRIEGL.
